CORNER PAD AND BLANK
Martin E. Dell, Patterson, N.C.
Filed June 24, 1963, Ser. No. 289,955
6 Claims. (Cl. 248—345.1)

The present invention relates to a corner pad construction for protecting the corners of furniture or the like during shipping or other handling and more particularly to an improved trihedral corner pad and blank therefor.

It is usual practice in the shipping or other handling of furniture and the like to package such furniture in crates or cartons and to provide corner pads of suitably folded paperboard material around each of the corners of the furniture to prevent the corners from becoming damaged during such handling. The most common type of conventional corner pads are those which comprise blanks folded into trihedral angle arrangements.

While providing some measure of shock absorption and protection, these conventional trihedral corner pads have the undesirable characteristic of frequently becoming unfolded during handling thereof since the same rely solely upon friction between the side edges of the plies of the walls of the corner pads. Prior attempts to solve this problem have not proved successful solutions since the same require a greater amount of paperboard material which increases the cost and renders the same undesirable due to economic considerations.

It is therefore an object of the present invention to provide a novel trihedral corner pad and blank therefor wherein the inner face plies of all three walls thereof and portions of the blank defining such plies when folded have cooperating cutouts and protuberances for positively interlocking the same in folded condition to maintain the corner pad in its trihedral angle arrangement.

In addition, these conventional trihedral corner pads have two of the three walls thereof of the required number of plies to provide the desired shock absorbency and the remaining wall thereof of at least one more ply than said two walls due to the manner of folding of the blanks forming these corner pads. In this regard, applicant has discovered that the preferred construction for corner pads of this type is to have each wall of the trihedral corner pad to be formed of three plies of the paperboard material which will provide sufficient shock absorbency for most uses. A conventional trihedral corner pad having three plies in two of the walls will have four plies in the third wall and therefore an excess of paperboard material is required which renders the conventional corner pad expensive to manufacture.

Therefore, it is another object of the present invention to provide a trihedral corner pad wherein each wall comprises three plies of paperboard material, which three plies of paperboard material are formed with a savings of material and wherein the corner pad is less expensive to manufacture.

Some of the objects of the invention having been stated, other objects will appear as the description proceeds, when taken in connection with the accompanying drawings, in which—

FIGURE 1 is a plan view of a corner pad blank incorporating the features of the present invention;

FIGURE 2 is a plan view of a triangular insert to be used with the blank shown in FIGURE 1;

FIGURES 3 through 5 are perspective views illustrating the manner of folding the blank and triangular insert shown in FIGURES 1 and 2;

FIGURE 6 is a front elevational view showing a corner pad incorporating the features of the present invention; and

FIGURE 7 is a sectional view taken substantially along line 7—7 in FIGURE 6.

2

Referring now to the drawings and more particularly to FIGURE 1, there is shown a corner pad blank 10 of suitable paperboard material and which includes first and second upper rectangular panels 11, 12 which are hinged together along a fold line 13 defining the adjacent side edges thereof. A lower rectangular panel 14 is hinged to the lower side edge of first upper panel 11 along a fold line 15 and a triangular lower panel 16 is hinged to the lower side edge of second upper panel 12 along a fold line 17. Triangular lower panel 16 is separated from lower rectangular panel 14 by a cut line 20 and is of substantially right-triangular configuration and has the side edge thereof corresponding to the hypotenuse thereof extending from the lower outside corner of second upper panel 12 to the proximal lower corner of lower rectangular panel 14.

First and second upper rectangular panels 11 and 12 and lower rectangular panel 14 have diagonally extending pairs of spaced fold lines 21, 22; 23, 24; and 25, 26 therein, respectively, which cooperate with each other and the hypotenuse edge of triangular panel 16 to substantially define a square. Fold lines 21, 22, 23, 24 and 25, 26 are spaced apart a distance slightly exceeding the thickness of the paperboard material of which the blank 10 is formed and divide panels 11, 12 and 14 into two right-triangular semi-panel portions 30, 31; 32, 33; and 34, 35, respectively, which form respective outer and inner face plies of the walls 36, 37 and 38 of a corner pad 40 when blank 10 is folded thereinto.

First and second upper panels 11 and 12 have cutouts 41, 42 formed in the side edges thereof remote from the fold line 13 hinging the two panels together. Cutouts 41, 42 extend from the upper outside corners of panels 11 and 12 downwardly for a predetermined distance and at a predetermined depth which slightly exceeds the thickness of the paperboard material of which blank 10 is formed. The remaining portions 43, 44 of these side edges from the lower ends of cutouts 41, 42 to the lower outside corners of first and second upper panels 11, 12 define protuberances which are received (FIGURE 6) in cutouts 45, 46, respectively, formed in the outside side edges of lower rectangular panel 14 remote from triangular panel 16 and from fold line 15, hinging panel 14 to first upper panel 11 when blank 10 is folded. Cutouts 45 and 46 extend respectively from the upper outside corner of panel 14 adjacent first upper panel 11 downwardly and from the lower corner of panel 14 proximal to triangular panel 16 toward the lower outside corner of lower rectangular panel 14 for predetermined distances which are substantially equal to the lengths of remaining portions 43, 44 of the side edges of upper panels 11, 12.

The remaining portions 47, 48 of the side edges of lower rectangular panel 14 between the ends of cutouts 45 and 46 and the lower outside corner of panel 14 define protuberances of a length not exceeding the length of cutouts 41, 42 in the side edges of upper panels 11, 12. Remaining portions 47, 48 are received in cutouts 41, 42 when blank 10 is folded and cooperates with remaining portions 43, 44 and cutouts 45, 46 to positively interlock the inner face plies 31, 33 and 35 of the walls 36, 37 and 38 of corner pad 40.

Referring now to FIGURE 2, there is shown an insert 50 of isosceles triangular configuration which has a fold line 51 extending between the apex and the base at the medial portion thereof. Fold line 51 separates insert 50 into two right-triangular semi-panel portions 52, 53 which are of an area slightly less than the area of lower portions 30, 32 of upper rectangular panels 11 and 12.

It is noted that two triangular inserts 50 are formed upon the severance of four of the blanks 10 from a sheet of the paperboard material and that the sides correspond-

ing to the hypotenuse of the right-triangular portions 52, 53 correspond to the hypotenuse side edge of triangular panel 16 of blank 10. Therefore, a substantial savings in the paperboard material is effected in the use of triangular insert 50 for providing the third ply in walls 36, 37 of the corner pad 40.

Referring now to FIGURES 3, 4 and 5, the manner of folding blank 10 and insert 50 is illustrated. Firstly, the insert 50 is placed in superposed relation to lower portions 30, 32 of first and second upper panels 11 and 12 and panels 11 and 12 are then folded along fold lines 21, 22 and 23, 24 to bring upper right-triangular portions 31, 33 into overlying relation to portions 52, 53 of triangular insert 50 and lower portions 30, 32 thereof. Portions 52, 53 of triangular insert 50 are therefore sandwiched between the portions of upper panels 11 and 12.

Upper panels 11 and 12 are then folded upwardly along fold lines 15 and 17 into right-angular relation to lower rectangular panel 14 and lower triangular panel 16. It is noted that fold line 17 is spaced upwardly from fold line 15 a distance substantially the same as the thickness of the paperboard material. The folded upper panels 11 and 12 and triangular insert 50 are then folded along fold lines 13 and 51 which brings triangular panel 16 into overlying relation to upper portion 34 of lower rectangular panel 14.

Lower rectangular panel 14 is then folded along fold lines 25 and 26 to bring the lower portion 35 thereof into overlying relation to triangular panel 16 and to position the remaining portions 47, 48 thereof in the cutouts 41, 42 in the upper rectangular panels 11 and 12 and to position the remaining portions 43, 44 of these upper panels in the cutouts 44, 45 in the lower rectangular panel 14. Corner pad 40 is thusly formed wherein walls 36, 37 and 38 are of uniform thickness and the innermost plies 52, 53 (FIGURE 7) of walls 36, 37 are formed by triangular insert 50 which is formed upon the formation of two of the blanks 10.

It is therefore believed apparent that a novel trihedral corner pad and blank therefor is provided wherein positive interlocking of all three walls of the corner pad is provided to prevent the corner pad from becoming unfolded and wherein savings of paperboard material is effected in the formation of the corner pad.

In the drawings and specification there has been set forth a preferred embodiment of the invention and, although specific terms are employed, they are used in a generic and descriptive sense only and not for purposes of limitation, the scope of the invention being defined in the claims.

I claim:

1. A corner pad for protecting the corners of furniture or the like during shipment or other handling, said corner pad comprising first, second and third walls interconnected and arranged to define a trihedral angle, said first, second and third walls each including first and second plies of substantially right-triangular configuration and interconnected along a fold line corresponding to the hypotenuses thereof and defining outer and inner face plies of said walls, an isosceles triangular insert having a fold line dividing the same into two right-triangular portions interconnected along the fold line, said right-triangular portions of said insert being disposed between said first and second plies of said first and second walls to define third plies therein, and a substantially right-triangular third ply disposed between said first and second plies of said third wall and being interconnected with the outer face ply of said second wall along a fold line corresponding to the lower side edge of said second wall outer face ply.

2. A corner pad for protecting the corners of furniture or the like during shipment or other handling, said corner pad comprising first, second and third walls interconnected and arranged to define a trihedral angle, said first, second and third walls each including first and second plies of substantially right-triangular configuration interconnected

along a fold line corresponding to the hypotenuses thereof and defining outer and inner face plies of said walls, and a substantially right-triangular third ply sandwiched between said outer and inner face plies, the inner face plies of said first, second and third walls having cooperating protuberances and cutouts in the adjacent sides thereof for locking the plies in folded condition for maintaining said walls in the trihedral angle arrangement.

3. A corner pad for protecting the corners of furniture or the like during shipment or other handling, said corner pad comprising first, second and third walls interconnected and arranged to define a trihedral angle, said first, second and third walls each including first and second plies of substantially right-triangular configuration and interconnected along a fold line corresponding to the hypotenuses thereof and defining outer and inner face plies of said walls, the inner face plies of said first and second walls having cutouts in the lower side edges thereof and extending from the lower inside corner of said inner face plies toward the outside corner thereof for a predetermined length less than the length of said lower side edges, the inner face ply of said third wall having cutouts in the side edges thereof in proximity to said first and second walls and extending from the outside corners of said third wall toward the inner corner thereof for a predetermined length at least as great as the distance between the lower outside corners of said inner face plies of said first and second walls and the cutouts in said lower side edges thereof, and the remaining portions of the lower side edges of the inner face plies of said first and second walls and the remaining portions of the side edges of the inner face ply of said third wall having the cutouts therein defining protuberances respectively disposed in the cutouts in the inner face ply of said third wall and the inner face plies of said first and second walls to lock these plies together in folded condition for maintaining the first, second and third walls in the trihedral angle arrangement.

4. A corner pad for protecting the corners of furniture and the like during shipment or other handling, said corner pad comprising first, second and third walls interconnected and arranged to define a trihedral angle, said first, second and third walls each including first and second plies of substantially right-triangular configuration and interconnected along a fold line corresponding to the hypotenuses thereof and defining outer and inner face plies of said walls, the inner face plies of said first and second walls having cutouts in the lower side edges thereof and extending from the lower inside corner of said inner face plies toward the outside corner thereof for a predetermined length less than the length of said lower side edges, the inner face ply of said third wall having cutouts in the side edges thereof in proximity to said first and second walls and extending from the outside corners of said third wall toward the inner corner thereof for a predetermined length of substantially the same as the distance between the lower outside corner of said inner face plies of said first and second walls and the cutouts in said lower side edges thereof, the remaining portions of the lower side edges of the inner face plies of said first and second walls and the remaining portions of the side edges of the inner face ply of said third wall having cutouts therein defining protuberances respectively disposed in the cutouts in the inner face ply of said third wall and the inner face plies of said first and second walls to lock these plies together in folded condition for maintaining the first, second and third walls in the trihedral angle arrangement, an isosceles triangular insert having a fold line dividing the same into two right-triangular portions interconnected along the fold line disposed between said outer and inner face plies of said first and second walls and defining third plies of said first and second walls, and a substantially right-triangular third ply disposed between said outer and inner face plies of said third wall and being

interconnected with the lower side edge of the outer face
ply of said second wall along a fold line.

5. A paperboard blank foldable into a trihedral corner pad having triangular walls, said blank comprising first and second rectangular upper panels hinged together along a fold line defining the adjacent side edges thereof, a rectangular lower panel hinged to the lower side edge of said first upper panel along a fold line, a substantially right-triangular lower panel hinged to the lower side edge of said second upper panel along a fold line and being separate from and beside said rectangular lower panel and having the side edge defining the hypotenuse thereof extending between the lower outside corner of said second upper panel and the lower proximal corner of said rectangular lower panel, said rectangular panels having diagonal fold lines therein separating the same into two right-triangular semi-panel portions, said diagonal fold lines and the hypotenuse edge of said triangular lower panel substantially defining a square, the side edges of said first and second rectangular upper panels remote from the fold line along which the same are hinged together having cutouts of predetermined length and depth therein, and the side edges of said rectangular lower panel remote from said first rectangular upper panel and said triangular lower panel having cutouts therein of predetermined length, the remaining portions of these side edges of said rectangular lower panel being of a length not exceeding the length of the cutouts in the side edges of said first and second rectangular upper panels and defining protuberances so positioned as to mate with the cutouts in the side edges of said first and second rectangular upper panels when the blank is folded to form the trihedral corner pad.

6. A paperboard blank foldable into a trihedral corner pad having triangular walls, said blank comprising first and second rectangular upper panels hinged together along a fold line defining the adjacent side edges thereof, a rectangular lower panel hinged to the lower side edge of said first upper panel along a fold line, a substantially right-triangular lower panel hinged to the lower

35
40

side edge of said second upper panel along a fold line and being separate from and beside said rectangular lower panel and having the side edge defining the hypotenuse thereof extending between the lower outside corner of said second upper panel and the lower proximal corner of said rectangular lower panel, said rectangular panels having diagonal fold lines therein separating the same into two right-triangular semi-panel portions, said diagonal fold lines and the hypotenuse edge of said triangular lower panel substantially defining a square, the side edges of said first and second rectangular upper panels remote from the fold line along which the same are hinged together having cutouts extending uninterruptedly downwardly from the upper outside corners thereof toward the lower outside corners for a predetermined length less than the length of the side edges thereof, the remaining portions of said side edges of said upper panels being of a given length, and the side edges of said rectangular lower panel remote from said first upper panel and said triangular panel having cutouts therein extending uninterruptedly from the upper outside corner of said rectangular lower panel and from the lower corner thereof adjacent said triangular panel toward the outside corner of said rectangular lower panel for a predetermined length substantially the same as the given length of the remaining portions of said side edges of said upper panels, the remaining portions of the side edges of said upper panels and the remaining portions of the side edges of said rectangular lower panel defining protuberances so positioned as to respectively mate with the cutouts in the side edges of the rectangular lower panel and the cutouts in the side edges of the upper panels when the blank is folded to form the trihedral corner pad.
